CLAIM

The ornamental design for a shower caddy, as shown and described.

DESCRIPTION

FIG. 1 is a perspective view of the shower caddy according to the invention;

FIG. 2 is a side view of the shower caddy as shown in FIG. 1;

FIG. 3 is a front view of the shower caddy as shown in FIG. 1;

FIG. 4 is a back view of the shower caddy as shown in FIG. 1;

FIG. 5 is a top view of the shower caddy as shown in FIG. 1; and,

FIG. 6 is a bottom view of the shower caddy as shown in FIG. 1.

The broken-line disclosure of suction cups and shower head in the views is for illustrative purposes only and forms no part of the claimed design.
